Attorney

UNITED STATES PATENT OFFICE.

MAMIE L. CAVIN, OF BAKER, OREGON.

HAIR CURLER.

Application filed May 18, 1923. Serial No. 639,856.

To all whom it may concern:

Be it known that I, MAMIE L. CAVIN, a citizen of the United States, residing at Baker, in the county of Baker and State of Oregon, have invented certain new and useful Improvements in Hair Curlers; and I do hereby declare the following to be a full, clear, and exact description of the invention, such as will enable others skilled in the art 10 to which it appertains to make and use the same.

This invention relates to a hair curler.

It is aimed to provide a novel construction or means whereby the essentials necessary 15 to efficient curling of the hair, for instance, heat, time and application of the curler while the hair is damp, may be advantageously practiced in an electrically operable and comparatively inexpensive form.

20 Additional objects and advantages will be pointed out or become apparent from a consideration of the description following taken in connection with accompanying drawings illustrating an operative embodiment.

In said drawings:—

Figure 1 is a perspective view of the device complete;

25 Figure 2 is a front end elevation;

Figure 3 is a rear end elevation;

30 Figure 4 is a longitudinal sectional view through the curling iron and

Figure 5 is a perspective of the spring employed.

35 Like reference characters designate like or similar parts in the different views.

In carrying out the invention, an iron is provided as at A which may be of any suitable size, shape or material which is adapted 40 for detachable connection to an ordinary electrically operable curling iron holder by means of a suitable attaching shank 10 in order to place the resistance 11 in a closed electric circuit so as to thereby heat the iron.

45 The iron A has a metallic covering or casting 12 which is formed into a stud 13 at the end opposite to shank 10. At the attaching end, iron A is laterally enlarged as at 14 and between the same and remainder of the 50 iron a notch or groove 15 is provided.

The hair is adapted to be wrapped about the iron A and is prevented from entering the groove 15 by a guard such as a pin or rod 16. The hair when thus wrapped is 55 preferably damp and it is clamped to the iron by a retainer or U-shaped clasp strip

17 which may be readily applied to or removed from the iron. This strip may be of suitable size and is preferably made of flexible metal.

60 The retainer or clasp 17 is carried by a bail 18 preferably made from a strand of resilient metallic wire and is fastened midway of its ends at 19 to the retainer or clasp 17. The end portions of the bail 18 are outwardly deflected or curved as at 20 and one of them terminates in an eyelet 21 adapted to be slipped over stud 13 and the other of which terminates in an attaching hook 22 adapted to surround the iron A at the groove 70 15 and be retained in said groove.

75 The curlers are preferably used in any suitable pluralities, the handle being attached successively to the shanks 10 of them in order to successively heat them. It will be realized that the irons will retain their heat for a considerable length of time and thus the user may follow ordinary pursuits about the home while they are in place in the hair. The use of the invention gives the 80 hair waves of sufficient permanence to last a number of weeks and thereby avoids the nightly used curl paper and the expense of the permanent wave.

85 It will be understood that the clasp 17 may be readily detached simply by disengaging the hook 22 from the groove 15 and thereafter disengaging eyelet 21 from the stud 13. The bowing or deflecting of the bail 18 at 20 enables the clasp 17 to accommodate various quantities of hair wrapped about the iron A, since the retainer 17 is fastened in the bail at its center and is free of the bail at its ends.

90 95 Various changes may be resorted to within the spirit and scope of the invention.

I claim as my invention:—

1. A curler having an iron about which the hair is adapted to be wrapped, a bail separable from and attachable to said iron, and a hair-retainer carried by said bail independently of the iron to coact with said iron.

100 105 2. A curler having an iron, a resilient bail associated therewith, and a hair-retainer unconnected at its ends to the iron and bail and engaged by the bail intermediate the ends of the latter and urged toward said iron.

110 3. A curler having an iron provided with a stud, a resilient bail having an eyelet engaging said stud, said bail having a hook to engage the iron, and a hair-retainer co-

acting with the iron and engaged by the bail intermediate the ends of the latter.

4. A curler having an iron, a bail associated therewith having a plurality of bows, said bail being of resilient material, and a hair retainer engaged by said bows at their junction, and said retainer at its ends being free of the bows.
5. A curler having an iron provided with a groove, a guard adjacent said groove to prevent entrance of hair thereinto, a stud extending from the iron, a resilient bail having

a plurality of loops, the free end of one of said loops being an eyelet engaging said stud, the free end of the other loop being a hook engaging said groove, and a hair retainer at its ends free of said loops and engaged by the bail intermediate said loops. 15

In testimony whereof I affix my signature in presence of two witnesses.

MAMIE L. CAVIN.
